FLANGED HEAD FOR PAPER CONTAINERS
AND METHOD OF MAKING THE SAMEGeorge Arlington Moore, Louisville, Ky., assignor
to Humoco Corporation, Louisville, Ky., a corporation of Delaware

Application July 17, 1934, Serial No. 735,562

20 Claims. (Cl. 93—51)

My invention relates to improvements in flanged articles composed at least in part of paper stock, or similar felted fibrous material and in the method of making the same, and the invention has for its object to provide a simple, efficient and strong article which can be formed from a substantially flat blank without rupture, distortion or other injury to the material, and which retains the shape or deformation imposed thereon by the drawing operation.

Further, said invention has for its object to provide an article of the character specified in which the walls thereof are composed of laminations or layers of material differing in properties or characteristics, such as paper and foil or similar metal, mutually contributing to enhance the strength of the structure and maintain the shape of deformation imposed thereon.

Further, said invention has for its object to provide an article of the character specified which is particularly adapted as an end closure or head for a container, and which, when so utilized, may be readily inserted in place to provide a smooth close fit with the body or shell of the container without buckling and is capable of being curled, rolled or otherwise worked to form a seam or joint with the container body without break-down or other injury to the flange.

Further, said invention has for its object to provide an article of the character specified in which the structure and shape thereof are particularly designed to form heads or end closures for container bodies of cross-section other than circular, such as bodies of oblong or oval shape or containers including curving portions, corners or sides of relatively short radius.

Further, said invention has for its object to provide an article of the character specified in which the arcuate flange portions thereof include means compensating for excess material resulting from reductions in radius in the flange and seam forming operations, allowing said operations without detriment to the material, and insuring the formation of a seam of uniform character.

Further, said invention has for its object to provide an article of the character specified in which the base portion and flange at the juncture thereof are reinforced to stiffen the structure, and provide a flexible connection between said flange and said base and an anchorage capable of interlocking with the seam plies to retain the same in place.

Further, said invention has for its object to provide an article of the character specified in which the straight side portions of the flange thereof include means for facilitating the folding over of the same in forming the joint or seam.

Further, said invention has for its object to provide an article of the character specified in

which the head includes means interposed between the arcuate end portions and the straight side portions of the flange to prevent said end portions from causing buckling, wrinkling or deformation of the straight portions when the head is inserted within the container body, and to maintain the parts in a smooth close fitting relation during the seam forming operation.

Further, said invention has for its object to provide an article of the character specified in which the bottom wall thereof is scored or weakened without impairment of the foil or of the impervious character thereof.

Further, said invention has for its object to provide an article of the character specified in which the laminated layers thereof are welded or vulcanized together by a flexible or elastic adhesive adapted to compensate without loss of adhesion for stresses or strains imposed on the laminations during fabrication and to enhance the strength and durability of said article and preserve the shape thereof.

Other objects will in part be obvious and in part be pointed out hereinafter.

To the attainment of the aforesaid objects and ends my invention consists in the novel features of construction and in the combination, connection and arrangement of parts, and in the steps constituting the method, hereinafter more fully described and then pointed out in the claims.

In the accompanying drawings:

Fig. 1 is a plan of a blank from which is produced one form of article constructed according to and embodying my said invention;

Fig. 2 is an enlarged sectional view thereof on the line 2—2 of Fig. 1;

Fig. 3 is a fragmentary section of apparatus for carrying out the method, the blank being shown in position to be operated upon;

Fig. 4 is a similar view showing the position of the parts after the blank is operated upon and the flanged article formed;

Fig. 4a is an enlarged section of a portion thereof illustrating the flange fluting and method;

Fig. 5 is an enlarged transverse cross-section of the flanged article taken on a line corresponding to the line 5—5 of Fig. 1;

Fig. 6 is a similar view showing how the marginal portion of the flange is turned in forming a container seam, the container body being shown in broken lines;

Fig. 7 is a longitudinal cross-section of the flanged article or head as formed from said blank, the same being shown positioned within a container shell or body;

Fig. 8 is a cross-section thereof taken on the line 8—8 of Fig. 7, looking in the direction of the arrows; and

Fig. 9 is a longitudinal cross-section of the container showing said flanged head and said container body interlocked to form a seam.

The flanged articles or heads 10 are preferably formed from blanks 10a of composite laminated structure comprising layers of materials of different qualities or characteristics mutually supplementing each other in satisfying the requirements of use. Paper stock alone, for instance, is difficult to work, and once the fibrous structure thereof is modified from its natural or flat state as by flanging, flowing, or other application of working pressure thereto it is more difficult to flow or turn the material after such treatment in order to form an interlocking seam or joint, and the stresses and strains imposed on the paper by the flanging operation ordinarily tend to cause the stock to expand or flare and lose the shape imposed thereon.

By using laminated blanks composed of superimposed layers of paper, preferably a long fiber, or rag stock which does not readily tear off in strata, and metal foil or other light sheet metal secured together by adhesive satisfying the requirements of the process and of the product, the shaping or flanging operation can be greatly facilitated and the flange can be later subjected to the seam forming operation and retained in folded position within the seam without becoming cracked, torn or otherwise injured. Further, in using foil or similar soft, readily deformable material the wall of the structure is rendered substantially impervious to air and moisture, and the paper component, because of its greater tenacity or tensile strength compared to the foil, serves to reinforce and strengthen said foil to prevent injury thereto.

The blank 10a, as one example, comprises a layer of foil 11 reinforced or strengthened at one side by one or more paper layers 12 and 13 preferably disposed with the fibres in crossing relation to form a structure like a veneer and secured together by an adhesive 14a of a character capable of forming with the paper a relatively stiff backing for the foil component, a fairly heavy vegetable glue or adhesive being found satisfactory for this purpose. The foil 11 is secured to the paper by an adhesive 14 of different properties from the adhesive 14a as hereinafter described. The opposite side of the foil is exposed, and the surface of the foil at the inner side thereof is embossed or roughened, as indicated at 15.

In forming the flanged article 10 from the laminated blank 10a, and in folding the marginal portion of the flange as shown in Fig. 6 at A, the layer or lamination at the outer side of the various bends turns over on a longer radius than the lamination at the inner side of the bends, and, in forming the curving end flange portions and upon turning over such curving end flange portions in forming a seam ply, the materials of the laminations become displaced relative to each other in accordance with the differences in reduction of radius resulting from said operations. It is therefore necessary to compensate for this by providing an adhesive which allows the laminations to slip, yield or otherwise move over each other during the flanging and seam forming operations and retains said laminations in intimate contact so that the stresses applied to the material will not rupture, break, tear, crack or otherwise damage the same, or cause the laminations or walls to wrinkle, buckle or become unduly irregular in outline.

I have discovered that certain substances having elastic or yielding properties, such as adhesives having bases of gutta-percha, caoutchouc or rubber, for example, substances containing latex, which usually require a solvent to place the same in condition for use, or other substances not requiring the use of a solvent, such as those containing chlorinated diphenyl resins as their base, are sufficiently flexible or resilient to yield when the material is being deformed to allow relative movement of the laminations and retain the layers in intimate contact, the article being formed without damaging the material or impairing the imperviousness thereof. I also find that such flexible or elastic substances or adhesives do not appreciably harden, crack or crystallize, are impervious to and unaffected by moisture, and compensate for stresses or strains imposed on the laminations without releasing the adhesion between the same so that the laminations are retained in intimate contact and to shape, thereby enhancing the durability, strength and impervious qualities of the article. In practice better results are obtained in forming the blanks by depositing a thin coat or film of the adhesive 14 on the metal foil and also upon the paper and then applying the paper to the foil. This appears to improve the gripping or sticking action of the adhesive, and further improvement is noted if the foil is embossed or otherwise roughened, as at 15, to provide anchorage for the adhesive 14. The articles 10 are preferably formed in dies such as shown at Figs. 3 and 4 with the application of heat. The heat either causes the adhesive to set, as in the case of those containing a rubber base, or renders the adhesive more flexible and resilient and causes the same to more uniformly permeate the fiber and the juncture between the paper and foil, as in the case of heat responsive adhesives containing a resin base, and setting upon cooling. The adhesive 14 retains the parts in permanent shape with the laminations intimately united in a manner simulating vulcanization or welding.

The laminated blank 10a although illustrated herein as being of greater length than width and adapted to form heads for containers of oval or oblong cross-section as shown as Fig. 8 may be of any desirable shape. Blank 10a as illustrated comprises a central portion 16 adapted to form the base or body of the flanged article or head and an outer part 16a adapted to form the flange on said article. The juncture between the central part 16 and the flange forming part 16a is designated by the broken line 17 having the arcuate end portions 17a. The flange forming part 16a comprises marginal side portions 18 having the edges 19 thereof lying on straight lines and the marginal end portions 20. The outer parts of the marginal portions 20 are serrated or notched, as indicated at 21, the blunt apices of the projections lying on outer arcs, designated by the broken lines 22, and the apices of the intervening spaces lying on inner arcs, designated by the broken lines 23. The arcs 22 and 23 at each end of the blank are drawn concentrically on radii having the center C. Each arc 23 is located substantially medially between the contiguous arc 22 and the contiguous arcuate portion 17a of the line 17.

The radial notches 21 are very effective in compensating for excess material in the arcuate end portions 20 of the blank when the flange is drawn, the edges of said notches drawing together as at 21a to compensate for the reduced

radius of said arcuate flange portions compared to the original radius of the curved margins 22. The function of said notches and the results produced thereby are more fully described hereinafter.

I have found however that in forming flanged heads of greater length than width, there is a tendency for the material of the notched arcuate end portions 20 to spread out, and exert compression pressures upon the straight side portions 18 of the flange, either causing or tending to cause the latter to buckle or to otherwise become distorted, or, because of the resistance of the relatively stiff side portions to said spreading effect at the rounded ends, causing said end portions 20 to flare outwardly from a vertical, and that, when the head is forced into place within the container body 25, the compression pressures exerted upon said side portions 18 by the end portions 20 in assuming a vertical position cause buckling, ruffling or other distorting effects.

While the notches 21 aid in preventing buckling, ruffling, folding or overlapping of the material of the flange when the head is inserted in the container body, I find it necessary, in forming structures having straight side portions such as herein described, to supplement such notches 21 by provision of notches 24 of modified shape located substantially at the junctures between the arcuate end portions 20 and the straight side portions 18 for preventing said distorting tendency and insuring a smooth, close fitting engagement between the parts throughout, and particularly coextensively with the uninterrupted inner part of the flange. The juncture notches 24 have relatively blunt apices 24a terminating well above the flange base line 17 and substantially in line with the arcs 23 at points coincident with the junctures between the curving portions 20 and side portions 18. When the flange is drawn the edges of the notches 24 draw closer together to prevent or minimize the distorting effect of the end portions 20 upon the side portions 18 and to form said flanges 16a with the end portions 20 thereof substantially vertical. By constructing the notches 24 with the blunt apices 24a, when the flange is drawn, the resulting notches 24b reduce in size and remain of sufficient depth and width to allow the flange portions 20 to assume a position more closely approaching the vertical so that the head can be inserted within the container without exerting compression pressures upon the side portions 18 tending to wrinkle, ruffle or buckle the same, the notches 24b as reduced also compensating for any compression pressures exerted whereby to obtain the smooth, close fitting relationship between the parts required for the seam forming operation.

I also provide means for facilitating the flange flowing or turning operation which comprises a series of longitudinally extending, parallel flutes 27 of substantial depth formed as hereinafter described in the inner surfaces of the straight flange portions 18 during the flange drawing operation, the flange portions 18 having substantially smooth, flat outer surfaces 18a.

The fluting 27 forms a wall of alternately reduced and enlarged thickness, the material along the longitudinal lines of reduced thickness 18b being highly compressed relative to the material along the lines of greater thickness 18c. The lines 18b of compressed material thus form reinforcements extending longitudinally of the side portions and contributing to maintain the walls

thereof vertical and in close fitting relation with the contiguous surfaces of the shell 25, and provide transversely a succession of lines of bend for facilitating the turning over of the flange in the seam forming operation. The fluting 27 is also very effective in mechanically locking the foil and paper plies 11-12-13 together to prevent separation or fraying thereof at the flange edge.

The fluting 27 is particularly adapted for facilitating the turning over of straight flange portions in forming seams for containers of the particular shape herein shown and described, and thereby compensating for the relatively greater resistance of non-arcuate or straight flange walls 18 to the turning or curling operation compared to the resistance of the end portions 20 of the flange 16a which may be more readily turned over because of the notches 21 and arcuate shape thereof, the turning over of such arcuate portions being inwardly radially towards the center. However, in the formation of seams or reinforcements for containers of other forms, the fluting 27 can be advantageously employed for facilitating the flowing or curling of arcuate flange portions.

The fluting 27 also cooperates with the notches 21 and 24 and with the foil component of the flange in obtaining the smooth uniform, close fitting relation between the flange 16a and body 25 desirable for proper coaction with the seam forming tools, and also places the material of the relatively stiff straight side portions 18 in condition to be responsive to the curling operation to the same extent as the material of the notched arcuate end portions 20, thereby enabling a uniform turning over of the flange throughout the extent thereof without breakdown of the material or dislocation of the head 10 because of the excessive pressures which would otherwise be required to effect the curling over of the material.

At Figs. 3 and 4, I have illustrated one form of apparatus or die for carrying out the method and forming the article or head 10a from the particular blank 10 shown and described in this application. With changes in the form of the product as may be extensively made within my invention, there will, of course, be corresponding changes in the form of the apparatus or dies employed.

Referring to Figs. 3 and 4, a female die 28 is shown supported in the die bolster 29, which may comprise a heating chamber 30, which facilitates the drawing operation and causes vulcanization of the laminations as above described. Die 28 is of hollow formation with a flat table or flange 31 at the top thereof for receiving the blank 10a properly centered thereon. The table 31 and inner wall 32 of die 28 meet in a rounded corner 33 to avoid breakage of the blank in the drawing operation.

The undrawn blank 10a is confined by the hollow pressure or stripper member 34 to which pressure is applied as through suitable spring clamps 35 detachably engaging the member 34 and retaining the same against upward movement, the pressure member as thus retained serving to hold the blank flat and keep it smooth during the drawing operation. The pressure applied to the blank 10a by the member 34 is not sufficient to retard materially the movement of the material inwardly upon the table 31 during the drawing operation. Downward movement of the stripping member 34 is limited by engagement of the marginal flange portion 37 thereof

with the bolster 29, and the spacing between the table 31 and member 34 is gauged in accordance with the thickness of the blank used so as to put the latter under the required restraint without 5 clamping the material to the extent of interfering with the drawing operation.

In the drawing and head forming operation, I preferably make use of dies 39 and 40 which are constructed to initially form a reinforcement 10 or rib 38 about an intermediate portion of the blank at the juncture of the base portion 16 thereof with the flange portion 16a thereof, said rib providing a complementary groove 38a within the flanged head for the purpose herein- 15 after described.

The anvil die 39 is adapted to slide within the die 28 and has a flat upper surface 41 which in the uppermost position thereof is substantially flush with the table 31. The die 39 has a 20 peripheral groove 42 at the upper end thereof adapted to receive the projecting male portion 43 on the die 40, the groove 42 and portion 43 being shaped to form a rib 38 of the cross-section shown at Fig. 4. The die 39 has a stem or shaft 25 44 slidably projecting through the lower end of the bolster 29 and engaged by a relatively strong spring 45, preferably of the leaf type, for yieldably resisting the downward movement of said die and imposing a brake resistance thereon, 30 such downward movement being limited by engagement of the die with the base of the bolster 29 and upward movement thereof being limited by engagement of the shoulder 46 on the projecting portion of the shaft 44 with the bottom of 35 said bolster 29.

The upper die member 40 is mounted for sliding movement within the pressure member 34, and is provided at its lower end with a recess 47 formed by the depending, peripheral, male rib 40 forming portion 43. Disposed within the recess 47 is a pressure plate or stripper member 48 having a shaft or stem 49 slidably mounted in the die member 40. Coil spring 50 is disposed about the rod 49 between the members 40 and 48.

45 In operation, the upper die parts 34, 40, 48 are lifted out of the way and the blank 10a is disposed in position upon the anvil die 39 and table 31, it being preferable to dip the blank first into a suitable substance for lubricating the dies 50 and rendering the material more responsive to the action thereof. I find that a wax, such as paraffine, is suited for this purpose because it becomes fluent at the temperatures employed in the flanging operation, and serves to improve 55 the hermetic seal between the shell and the head. The parts 34, 40, 48 are then replaced in position, as shown in Fig. 3, with the pressure member 34 secured in engagement with the marginal portion of the blank to function in the manner above 60 described, and with the member 48 engaging the central portion 16 of the blank 10a, corresponding to the flat base portion 51 of the head, and retaining such central portion in firm engagement with the anvil die 39 to hold the blank in 65 position during the rib forming and flange drawing operation. Upon application of power, the male die 40 descends against the tension of the spring 50 while the die member 39 remains stationary, the operation causing the male portion 70 43 to enter the recess 42 and drawing the material from the marginal portion of the blank into the recess 42 to form the rib or reinforcement 38. The deformation or shape imposed on the material conforms to the shape of the spacing or 75 clearance between the portions 42 and 43 pro-

vided when the lower surface 52 of the die 40 engages the member 48 as shown at Fig. 4, it being understood however that, at the completion of this rib forming operation, the anvil die 39 is retained by the spring 45 substantially in the 5 position shown at Fig. 3.

When the rib forming operation is completed, the power applied to the die 40 becomes effective to move dies 39 and 40 as a unit relative to the parts 28 and 34 against the brake resistance of 10 the spring 45 which engages the outer end of stem 44 to complete the flange forming operation as shown at Fig. 4. During the flange forming operation the die members 39 and 40 remain engaged with the relatively flat central portion 51 15 and the rib portion 38 so that the flanging operation can be completed with the previously deformed material forming the rib 38 clamped between the dies to preserve the shape imposed 20 on the material by the rib forming operation. A clearance 53 of substantially the thickness of the flange is provided between the surface 32 of flange forming die 28 and the surface 54 of the die 40, the marginal portion of the blank being drawn into said clearance space 53 from between the 25 table 31 and pressure plate 34 by the joint movement of the dies 39 and 40. The surface 54 upon each of the flat sides thereof is provided with a series of longitudinally extending parallel recesses 55 into which the rods 55a are sweated 30 to provide the projecting ribs 55b for gripping the material during the flange drawing operation to more uniformly distribute the application of the force used in the drawing operation and to take the strain off of the base of the 35 flange being drawn, particularly at the arcuate ends thereof, the operation forming the fluted structure 27 above described.

When the flanging operation is completed the spring clamps 35 are disengaged and the power 40 applying means disengaged from the die 40, the parts then being returned by the spring 45 towards their uppermost position, and, upon removal of the pressure plate 34 and die 40, the spring 50 forces the stripper plate 48 outwardly 45 to cause disengagement of the flanged head from the die 40.

In the construction of containers, such as shown in Fig. 9 it may be advisable in some instances to form the heads 10 with weakened, 50 scored, or partially cut portions, as indicated at 55 56 in Figs. 5 and 6, to provide knock-outs 57 in the base portions of the heads 10 which may be readily pressed in by the finger or thumb, severed and removed. As shown in Figs. 5 and 6 55 a wedge-shaped cut 56 is made substantially through the paper component of the flat portion 51 of the head along a line contiguous to the bead 38. The apex of the cut terminates short of the foil 11 so that the knock-out 57 may be 60 formed without damaging the foil and impairing the impervious qualities thereof.

It is preferable, in some instances to form the knock-out 57 at the same operation with the formation of the flanged head and for this purpose, the die 39 upon the surface 41 thereof is provided with a wedge-shaped cutter 58 contiguous to the groove 42 and in position to operate upon the paper side of the blank, the depth of the cutter 58 being substantially equal to the 65 thickness of the paper lamination or laminations 12 and 13. The face of the stripping and pressure member 48 at the foil side of the blank is provided with a complementary groove or recess 59 registering with the cutter 58. 75

When the pressure is applied to the die 40 and the inner face 52 thereof engages the member 48 the pressure exerted causes the wedge-shaped cutter 58 to plow through the paper until the apex thereof reaches the elastic adhesive 14 between the paper and the foil, the plowing action spreading the material laterally so as to minimize compression on the foil tending to sever, bite into or otherwise damage the same.

10 The elastic adhesive 14 serves to cushion the compression on the foil, and the groove 59 allows the foil to yield and to be received into the same upon the application of compression to the foil, thereby preventing cutting, breaking or 15 other damage thereto as a result of the cutting operation. The original foil thickness is thus maintained substantially uniformly throughout, and the impervious property of such foil is preserved.

20 By the provision of a wedge-shaped cutter 58 gauged to plow substantially through the entire thickness of the paper layers into the elastic adhesive 14 short of the foil 11, I am able to form a knock-out 57 which is normally impervious to air and moisture and which may be readily pressed out and removed, the parts then exhibiting a clean shear at the severed edges.

After the blank 10a is drawn by the action of said dies, the central portion 16 of the blank 30 forms the bottom 51 and bead 38 of the flanged head 10 and the portion 16a forms the vertical flange including the side portions 18 and curved end portions 20. The reinforcement or bead 38 is formed at the junction between said bottom 35 51 and said flange 16a as hereinafter more fully described. The arcuate or curving end portions 20 thus formed each comprises a substantially continuous inner portion 60 which is not to be subjected to further folding or deformation and 40 the non-continuous or interrupted marginal portion 61 which is to be infolded together with the outer parts of the side flange portion 18 into interlocking relation with the marginal portions of the container body wall 25 hereinafter 45 described. The continuous portion 60 corresponds with the portion of the blank between the lines 17 and 23, and the interrupted portion 61 corresponds with the portion of the blank between the lines 22 and 23. In drawing the flange portions 20 the radius thereof is reduced from that of the end margins of the blank, represented by the lines 22, to that of the curved end portions 16a of the line of fold 17. This reduction in radius causes the edges of the notches 21 to 55 be drawn towards each other as shown in Figs. 5 and 7, forming notches 21a of reduced size compensating for the excess material resulting from the reduction in radius. It will be noted that the flange 16a is of substantial depth compared to the radius of the rounded or curved end portions 20 to provide ample material to be infolded in forming the seam 26 of the container.

When flanged heads are ordinarily drawn from a flat blank of paper stock only in the absence of notches the resulting reduction in radius tends to crowd, compress or pleat the excess material at the marginal portion of the flange causing the flange to expand or flare out and lose its shape. In my invention the foil layer 11 supplemented by the notches 21 opposes the tendency of the paper layer to expand, and, I am thus able to maintain the entire flange 16a substantially vertical. The notches 21a, supplemented by notches 24 also aid in preventing buckling, 65 wrinkling or ruffling of the flange, particularly in

the straight portions 18 thereof, when the head 10 is inserted within the body 25 as shown at Fig. 7.

In drawing flanged heads in ordinary practice without the preliminary notching of the blank, 5 the curved wall portions of the flange, particularly when of substantial depth compared to the radius thereof, become thick to compensate for the excess material, or tend to ruffle or pleat, and when said walls are compressed in the drawing operation the material of the wall becomes highly compressed, hardened and embrittled, rendering it difficult to turn over or flow the material in forming the seam without causing break down of such material. This difficulty is 15 obviated by the notching 21. The notching 21 also allows the flange 16a to be drawn without causing the foil at the curved ends to ruffle or pleat in compensating for the excess material thereof upon reduction in radius. If such foil 20 pleating or ruffling were allowed in the outer portions 61 of the curving flange portions 20, the material is liable to jam in the dies to cause rupture or other damage thereto or render the same 25 unsuited for the seam forming operation.

The lower part of the flange 16a is continuous throughout to provide an extended surface contact with the shell 25 and is made relatively stiffer and more rigid since such inner portion 30 is not to be subjected to further flowing or deformation operations but must sustain the forces applied to the margin during the curling operation.

In the present invention the notches 21 are of size compensating for reduction of radius in 35 forming the flange and for reduction in radius resulting from the turning over of the portion 61 in forming the seam 26 so that the use of excess material is obviated at the rounded ends 40 of the seam 26 of the container, and the entire 45 seam or reinforcement can be made of uniform cross-section and shape. In Fig. 6, I have shown the end flange portion 61 turned over, illustrating at 21b how the notch edges are drawn together to form a substantially continuous wall 45 or ply structure without crowding of the material, and insuring the formation of a container seam of uniform cross-section throughout.

The means 21 for compensating for excess material at the curving end portions of the 50 flange upon double reduction in radius is particularly applicable to containers having rounded portions of relatively short radius and to containers formed with rounded corners or sides when the flange depth is substantial compared to 55 the radius of the curved ends thereof.

The rib 38 of the head 10 serves to reinforce and stiffen the article about the margin thereof, and tends to retain the same in shape against warping due to shrinkage. The rib 38 provides a relatively 60 deep recess or groove 38a at the inner side of the head between the bottom 51 and the inner side of the flange 16a for receiving the lower portion of the reinforcing seam 26 as shown in Fig. 9. For this purpose the rib 38 comprises a wall portion 63 of substantially a 90 degree arc described about a center located on the opposing inner surface of the flange wall 16a and having a radius substantially equal to the total thicknesses of the plies of the joint 26 to be received and anchored in the groove 38a. The arcuate portion 63 at one end merges into a straight wall portion 64 substantially normal to the bottom 51 and at its opposite end merges into a straight wall portion 65 substantially normal to the flange wall 16a. 70 75

The rib 38 as thus constructed provides a yieldable or elastic connection between the bottom portion 51 and flange 16a, compensating for shrinkage as the article dries and tending to supplement the foil 11 in keeping the flange wall 16a substantially normal to the base against outward expansion. The yieldability of the rib 38 also facilitates the insertion of the head 10 into the socket 62 of the shell 25 and allows, supplementary to the notched formation 21a and 24, the head 10 to be forced into place without causing canting, buckling, wrinkling or other deformation of the flange 16a or bottom 51.

When the head 10 is utilized as an end closure 15 for the container body 25 as shown at Figs. 7 to 9, it is inserted in position with the head 38 resting upon or engaging the squared abutment or shoulder 66 formed in the container wall, the shoulder 66 and the portion 65 of the bead 38 having a 20 right angular interengagement, the corner of the bead 38 fitting into the corner of the shoulder 66. The seam 26 is then formed with the plies thereof received into and interlocking with the relatively deep groove 38a. The shoulder 66 effectively resists axial movement of the head 10 25 under the pressures or stresses applied lengthwise of the container and prevents the head from becoming dislodged therefrom when bending and canting strains are imposed thereon, the bead 38 and shoulder 66 cooperating to resist stresses and strains imposed on the container liable to cause distortion of the bead 38 and allow the seam plies to be released therefrom and loosened. It is to be understood that the other end of the 30 container may be provided with a similar end closure or head.

The foil 11 disposed within the groove 38a and upon the inner side of the flange 16a is brought, when the seam 26 is formed, into contact with 40 the contiguous ply portions of the seam 26 to form a gasket seal for preventing the passage of air and moisture through the joint or seam.

The width and the depth of the groove 38a allow the plies of the seam 26 to be forced into interlocking relation with the groove upon application of pressure lengthwise of the plies. The parallel or straight portions 64—16a of the groove 38a serve to prevent rocking or swinging of the interlocked end of the plies on the 90 degree arc 45 of the wall portion 63 out of engagement with the groove, the plies, in effect being keyed within said groove 38a against movement. The depth of the groove 38a is such that the extended plane 50 of the bottom 51 intersects all of the parallel plies of the seam including the flange ply 67 which is embedded between the ply portions 55 formed from the marginal portion of the body, and which has the end thereof extending into the confines of the groove 38a. When thus embedded 60 the rounded notched end portions 61 form substantially a continuous structure as shown in Fig. 6 at 21b.

The interlocking structure provided at 38a resists stress or pressure on the seam plies in all 65 directions. The bottom 51 serves as a brace or strut disposed inside of the seam body to resist inward movement or loosening of the plies thereof. Stress on the seam plies directed lengthwise thereof in either direction is resisted by the engagement between the loops or bends and complementary ends of the plies.

The structural features of the head 10 embodying my said invention are coordinated to provide a flanged head which may be fabricated from 70 a flat blank without distorting, breaking down,

embrittling or otherwise injuring the stock or material to an extent that it cannot be subsequently worked in forming the seam 26 of the container, which may be inserted into a container shell in a smooth, close fitting relation thereto without buckling, wrinkling or ruffling and which provides an inner flange portion having a continuous, extended, uninterrupted engagement with said shell.

The article embodying my said invention and resulting from the method thereof, when received into a container shell in a smooth, close fitting relation thereto may be readily turned over about the flange thereof together with the marginal portion of the shell to form a multiple ply joint 10 or seam of substantial strength, durability, and imperviousness to air and moisture, and said article or head is particularly adapted for containers of cross-sections other than circular, such as containers having curving wall portions of relatively short radius, and particularly to the container having straight side walls connected by curving side or corner portions of relatively short radii such as herein shown and described. The resulting container incorporating said head is 15 strong and durable, of light weight and pleasing appearance, and substantially impervious to air and moisture, forming a hermetically sealed package capable of preserving the contents thereof 20 in condition for prolonged periods. By employing the head embodying my said invention, the reinforced seam or joint 26 can be made of uniform gauge dimensions capable of being uniformly engaged by a suitable cover or closure.

In my invention the paper component of the head is reinforced or supplemented by a foil lamination which renders the head substantially impervious to fluids and preserves the shape imposed thereon by the drawing operation, and knock-outs such as herein shown and described, 40 may be formed in said heads without impairing the impervious character of the walls thereof.

Having thus described my invention what I claim and desire to secure by Letters Patent is:

1. The method of producing an article of the character described which comprises making a blank of paper stock and metal foil laminations with an elastic adhesive therebetween, and subjecting said blank to the action of dies for conforming the same to a desired shape.

2. The method of producing an article of the character described which comprises making a blank of paper stock and foil laminations with an elastic adhesive therebetween, and subjecting the blank to a deforming action in the presence 50 of heat.

3. The method of producing an article of the character described which comprises making a blank of paper and foil laminations with an interposed layer of an adhesive having a rubber 60 base, and deforming said blank in the presence of heat to form a flange at substantially right angles to the remainder of the article.

4. The method of producing an article of the character described which comprises making a blank of paper and foil laminations with an interposed elastic adhesive, and drawing a flange about the marginal portion of said blank, said flange being substantially at right angles to the remaining portion of the article.

5. The method of producing an article of the character described which comprises forming a laminated structure of paper and foil, and plowing into the paper lamination and spreading the material laterally to form a wedge-shaped cut 75

therein and minimize compression on the foil lamination.

6. The method of producing an article of the character described which comprises forming a laminated structure of paper and foil, and forming a cut in the paper lamination, while relieving at the opposite side of the structure compression on the foil.

7. The method of producing an article of the character described which comprises forming a laminated structure of paper and foil with an elastic adhesive therebetween, plowing into the paper to form a wedge-shaped cut therein and spread the material laterally to minimize compression on the foil while relieving at the opposite side of the structure any compression on the foil.

8. The method of producing an article of the character described which comprises forming a laminated blank of paper and foil with an adhesive therebetween, subjecting said blank to the action of dies for imposing a deformation thereon, and at the same operation subjecting the paper component of said laminated blank to a scoring operation while leaving the foil component substantially intact.

9. The method of producing a flanged article which comprises making an oblong blank having notched arcuate end portions and non-arcuate side portions from paper and foil laminations secured together with an elastic adhesive, retaining the marginal and central portions of said blank in position while subjecting the intermediate portion thereof to the action of die members for forming a relatively deep groove therein, and then drawing the flange at the marginal portion of said blank by the joint movement of said die members against a spring resistance while retaining said central and intermediate portions of the material under pressure between said die members to preserve the shape imposed on the material in forming said groove.

10. An article of the character described comprising a body composed of fibrous material and foil secured together with an elastic adhesive, and including a peripheral flange drawn from the marginal portion thereof, said flange extending substantially at right angles to the remainder of the article.

11. An article of the character described comprising a body composed of fibrous material and foil secured together by an adhesive, said body including a peripheral flange about the margin thereof, and a groove formed therein at the juncture of the flange with the remaining portion of said body.

12. An article of the character described comprising a body composed at least in part of fibrous material, said body having substantially straight side flange portions having longitudinally extending flutes formed therein and arcuate end flange portions having notches formed therein.

13. An article of the character described comprising an elongated body composed at least in part of fibrous material and having relatively

straight side flange portions and arcuate end flange portions, and notches having blunt apices formed in said body at the junctures of said side and end flange portions.

14. An article of the character described comprising an elongated body composed of laminations of foil and paper stock, and including a peripheral flange having arcuate end portions and non-arcuate side portions, said end portions having notches formed therein to compensate for excess material resulting from reductions in radius, said side portions having means formed therein to facilitate inturning of the material thereof, and said end and side portions having notches at the junctures thereof of slightly greater width than the notches in said end portions.

15. An article of the character described comprising a body composed of laminated fibrous and metal foil material, and including a relatively flat base portion and a peripheral flange portion, said portions being connected by a yielding arcuate portion forming a groove therebetween, and said arcuate portion merging with said base and flange portions substantially normal thereto.

16. A laminated article having a score in certain of the laminae to provide a knock-out, and an elastic cushion between the scored and un-scored laminae.

17. A laminated article having a substantially flat portion and a score in certain of the laminae to provide a knockout, and having a portion of an un-scored lamina projecting above the surface of the flat portion in the plane of said score.

18. The method of producing an article of the character described which comprises making a blank of laminations of fibrous material and metal foil with an adhesive therebetween, subjecting said blank to the action of die members for scoring the fibrous material to provide a knock-out, the foil being retained in impervious condition, moving said members relative to another die member to form a reinforcement about said blank inwardly of the margin thereof, and drawing a flange about the marginal portion of said blank while retaining the intermediate portion thereof clamped between said members.

19. The method of producing an article of the character described which comprise making a laminated blank, subjecting said blank to the action of dies to score one of the laminations thereof while leaving another lamination intact to provide a knock-out, forming a peripheral reinforcement of arcuate form about said blank inwardly of the margin thereof, and drawing a flange about the marginal portion of said blank.

20. In an article of the class described, a laminated structure of fibrous material and foil, the fibrous material being substantially thicker than the foil lamina, and an adhesive for securing the fibrous lamina to the foil lamina, the peripheral portion of the structure including a substantially right angle flange connected to the central portion thereof by an arcuate portion.
